APPARATUS USEFUL IN DIRECTIONAL WELL DRILLING

Arthur L. Armentrout, Los Angeles, Calif.

Application April 4, 1941, Serial No. 386,851

3 Claims. (Cl. 255—1.6)

This invention pertains to well drilling equipment and relates more particularly to apparatus useful in directional well drilling operations.

In the drilling of deep wells, such as oil wells and gas wells, it is sometimes necessary to resort to what are known as directional drilling operations. Thus, it may be desired to direct the drilling tools toward a given earth formation or it may be necessary to change the direction of the drilling tools to straighten the well or to return the tools to the intended course. I will herein refer to such operations as "directional drilling," it being understood that this term is to be construed broadly to cover any and all well drilling operations where the well bore is to be given a pre-determined or undetermined direction different from its initial direction or is to be returned to its intended course at its lower end or at any other point.

Tools and methods of various kinds have been proposed and employed for carrying on directional drilling operations. So far as I am aware the drilling tools employed in such operations have been rotated and fed into the earth formation to form the side track bore or directional bore. The side tracking bit or drilling tool is usually deflected by a whip stock but other deflecting means have been employed. The deflection of the rotating drilling tool by any means whatsoever results in bending of the rotary well drilling string. The bending of the drilling string causes the drilling tool to whip and gyrate as it rotates so that it often takes a course quite different from that intended and there is no assurance that the drilling tool will proceed in the desired direction. For this reason directional well drilling operations are often unsuccessful. There are many other difficulties encountered in directional well drilling as now practiced and the directional drilling operations are usually prolonged and expensive.

A general object of this invention is to provide a simple, dependable directional well drilling method and a highly effective apparatus for carrying out the method.

Another object of the invention is to provide a practical method for the directional drilling of wells by means of which the drilling tool may be made to drill a side track bore or directional bore in any selected direction and at any selected reasonable angle relative to the initial direction of the well bore.

Another object of this invention is to provide a method useful in the directional drilling of wells that avoids rotation of the drilling tool employed

to form the side track bore or directional bore and, therefore, obviates the difficulties and uncertainties encountered in the operation of prior directional drilling tools.

5 Another object of this invention is to provide a method of the character referred to in which the bit or drilling tool may be very accurately oriented before starting the drilling operation and in which the direction of the tool is maintained throughout the drilling of the side track bore.

Another object of this invention is to provide a method of the character referred to which may be quickly performed and which may be carried out without installing whip stocks or other equipment that might obstruct the well or interfere with subsequent drilling operations.

Another object of this invention is to provide directional well drilling equipment by means of which the bit or drilling tool may be accurately oriented and given the desired angle of operation without employing a whip stock, or other expensive device liable to fail or become displaced.

Another object of this invention is to provide directional well drilling equipment embodying a percussive type bit and effective means for operating the bit to drill the side track bore or directional bore.

The various objects and features of my invention will be fully understood from the following detailed description of typical, preferred forms of the apparatus and a typical manner of carrying out the method of the invention, throughout which description reference is made to the accompanying drawings, in which:

30 Fig. 1 is a longitudinal sectional view of the lower portion of a well bore showing the apparatus of the invention in an initial position and illustrating the surveying device extended from the bit for operation. Fig. 2 is a view similar to Fig. 1 showing the directional drilling tool or bit in operation in the directional bore. Fig. 3 is an enlarged longitudinal detailed sectional view of the impact generating mechanism with the parts in the normal positions. Fig. 4 is an enlarged fragmentary longitudinal sectional view of the upper portion of the impact generator showing the floating plunger or follower. Fig. 5 is an enlarged fragmentary longitudinal detailed sectional view of the intermediate portion of the impact generator illustrating the hammer and its control means. Figs. 6 and 7 are enlarged transverse detailed sectional views taken as indicated by lines 6—6 and 7—7, respectively, on Fig. 3. Fig. 8 is a fragmentary longitudinal de-

tailed sectional view of the directional drilling bit and adjacent parts showing the surveying instrument oriented in the bit and Fig. 9 is a fragmentary side elevation of another form of directional drilling bit with the surveying instrument oriented therein.

The method and apparatus are capable of substantial variation to adapt them for use under various conditions and for the performance of different directional drilling operations. I will describe a typical use or application of the method and a typical form of the equipment, it being understood that this is merely illustrative and is not to be construed as limiting or restricting the invention to the particular features set forth. I will first proceed with a detailed description of the apparatus and will then describe the method.

The apparatus of the invention as illustrated in Figs. 1 to 8, inclusive, may be said to comprise, generally, a drilling string or operating string S having a curved or angular section 11, a percussive type drilling mechanism or impact generator 10 on the section 11, a directional drilling bit 12, and means 13 for orienting the bit 12 in the well preparatory to operation of the impact generator 10.

The operating string S serves to carry the several drilling elements and is tubular to conduct drilling fluid and to receive or pass elements of the orienting means 13. The string S is a tubular well string of tubing or drill pipe made up of sections or stands in accordance with the common practice. It is preferred to employ a string S which is considerably smaller in diameter than the well bore B so that the string or a lower portion of the string may assume a position at one side of the well as shown in Figs. 1 and 2. The string S formed of conventional tubing, drill pipe, or the like, is flexible to a substantial degree as will be appreciated by those skilled in the art.

The section 11 serves to carry the impact generator 10 and drilling bit 12 and is such that the bit 12 is offset from, out of alignment with, or at an angle to the longitudinal axis of the string S. The section 11 may be a length or section of drill pipe, well tubing, or the like, and is connected with the lower end of the string S by a suitable coupling or collar 17. In accordance with the invention the section 11 is bent, curved or made angular. It is preferred to give the section 11 its desired shape, curvature or angularity before introducing the equipment into the well bore B and the section 11 is sufficiently rigid to resist distortion and substantially maintains its shape when the tool is in operation. As illustrated in the drawings the section 11 may have a substantial curvature or angularity, with its upper part aligned with the string S and with its lower part extending downwardly and laterally at a substantial angle of the string. The curvature or angularity of the section 11 is such that the bit 12 is at one side of the bore B while the string S lies at the opposite side of the bore. The angularity of the section 11 is not so great that the equipment cannot be easily run into and out of the well. In accordance with the present invention the section 11 may be given any selected or required curvature or angularity to adapt the apparatus for use in any particular job and for any given purpose.

The percussive mechanism or impact generator 10 is operable by manipulation of the string S to impart downward impacts or blows to the section 11 to cause the bit 12 to drill the side

track bore or directional bore D as will be later described. In the preferred form of the invention the impact generator 10 is actuated by reciprocation or longitudinal movement of the operating string S. The impact generator 10 is connected between the curved or angular section 11 and the bit 12, having one end connected with the lower end of the section 11 and having its other end connected with the upper end of the bit 12.

The impact generator 10 is a telescopically assembled structure including an outer tubular member or body 14 and a mandrel 15 entering the body 14. In the arrangement illustrated the outer member or body 14 is attached to the curved or angular section 11 of the operating string S and the mandrel 15 carries the bit 12. A tubular sub 16 is attached to the lower end of the section 11 and a tubular part, which I will term a barrel 18, is connected between the sub 16 and the body 14. The sub 16 has a pin 19 threaded in the upper end of the barrel 18 and the lower end of the barrel is threaded in the upper part of the body 14. As shown in Figs. 3 and 4 the lower end of the barrel 18 forms a downwardly facing annular shoulder 20 in the tubular outer assembly of the impact generator 10. A tubular shoe 21 is provided on the lower end of the body 14. The shoe 21 may have a reduced upper portion threaded in the lower end of the body 14 and arranged and proportioned so that its upper end forms an upwardly facing annular shoulder 22 in the tubular body assembly. The tubular outer assembly 14, 18 and 21, just described, may be larger in diameter than the operating string S but is preferably much smaller in diameter than the well bore B to be received in the well with substantial clearance as shown in Figs. 1 and 2.

The mandrel 15 of the impact generator 10 slidably passes through the shoe 21 to project downwardly for connection with the bit 12. An annular upwardly facing shoulder 23 is provided in the shoe 21 and the mandrel 15 has an external annular flange 24 whose lower end is adapted to cooperate with the shoulder 23 to limit relative longitudinal movement between the mandrel 15 and the body 14. The portion of the mandrel 15 above the flange 24 is reduced in external diameter to leave an annular chamber in the body 14 and shoe 21. A hardened annular or tubular anvil 25 rests on the flange 24 or is secured to the mandrel 15 to bear on the flange. The outer tubular assembly 14, 18 and 21 and the mandrel 15 are keyed or clutched together for the transmission of rotation or turning forces when they are fully extended. In the particular case illustrated the mandrel flange 24 and the body shoulder 23 have engageable clutch parts 26 for the transmission of rotation.

The impact generator 10 further includes a hammer means operable by reciprocation of the string S to impart downward hammer blows or impacts to the anvil 25. This means includes an elongate tubular part of substantial weight which I will term the hammer 27. The hammer 27 is shiftable or slidable longitudinally in the body 14. In the preferred construction the upper and lower ends of the hammer 27 have notched or grooved peripheral flanges 28 for guiding the hammer in the body 14 while allowing free flow of fluid past or around the hammer during relative movement between the body and hammer. The tubular hammer 27 shiftable or slidably engages on the reduced upper part of the

mandrel 15. A replaceable hardened hammer head 29 is provided on the lower end of the hammer 27 for striking the anvil 25. I have shown the replaceable head 29 threaded and locked in the lower portion of the hammer 27 and formed to have the lower notched guide flange 28 of the hammer.

The hammer means or impact generator 10 further includes a mandrel or stem secured in the outer body assembly 14, 18 and 21 and arranged to pass through or into the hammer 27. In the preferred construction this stem is sectional comprising an upper section 30 and a lower section 31. The upper section 30 is fixed to the sub 16 and extends downwardly in the barrel 18 with substantial clearance to leave an annular chamber therein. The upper end of the section 30 may be fixed to the pin 19 of the sub 16. The lower section 31 is provided with an enlarged head 32 threaded on the lower portion of the section 30 and formed to leave or provide an annular downwardly facing shoulder 33 on the stem. The shoulder 33 lies in the same horizontal or transverse plane as the shoulder 28 and has grooves or notches 34 to permit a free circulation of fluid passed or around the head 32 when the impact generator 10 is in operation.

The lower portion of the stem section 31 is reduced in external diameter to leave or provide a downwardly facing annular shoulder 34. The shoulder 34 is spaced a considerable distance below the head 32 and is tapered or sloped downwardly and inwardly. The stem sections 30 and 31 are tubular to conduct fluid from the sub 16 to the tubular mandrel 15. The upper portion of the mandrel has an enlarged central bore or opening 35 which receives the reduced lower portion of the stem section 31. Packing 36 is provided on the stem section 31 to slidably seal with the wall of the opening 35. A gland 37 is threaded on the stem section 31 to support and compress the packing 36.

The hammer 27 is spring actuated or spring loaded and is controlled by an automatic latch means to be suddenly and forcibly driven against the anvil 25 during each down stroke of the string S and body 14. A coiled spring 38 is arranged in the body 14 under compression between the upper end of the hammer 27 and the shoulders 20 and 33. The spring 38 tends to drive or move the hammer 27 downwardly relative to the body 14 and mandrel 15. It is preferred to construct and proportion the spring 38 so that there may be a free flow of fluid through or around it and the notches 34 at the shoulder 33 provide for a free fluid movement through or passed the upper end of the spring.

The latch means for controlling the hammer 27 includes a semi-annular or partially annular latch block 39 slidably riding in a correspondingly shaped transverse slot 40 in the wall of the hammer 27. The block 39 has flat upper and lower sides shiftably engaging in the slot 40 and the lower side of the block is adapted to engage the upper end of the mandrel 15 to releasably hold the hammer 27 against downward movement with respect to the mandrel. The block 39 is provided with a downwardly and inwardly sloping inner surface 41 engageable by the shoulder 34 as will be later described. The outer surface of the block 39 may slope downwardly and outwardly. The block 39 is spring urged or spring held being urged inwardly by a leaf spring 42. The leaf spring 42 may be attached to a reduced portion of the hammer 27 by a bolt or screw 43.

The spring 42 urges the latch block 39 inwardly against the reduced lower part of the stem section 31.

When the body 14 of the impact producing means 10 is moved down relative to the mandrel 15, the block 39 engaging the upper end of the mandrel holds the hammer 27 against movement and the spring 38 is compressed and has additional energy stored therein. The body 14 moves downwardly until the pitched shoulder 34 cooperates with the pitched surface 41. This cooperation results in outward movement of the block 39 and the block is moved clear of the upper end of the mandrel 15. This releases the hammer 27 and the hammer is suddenly driven downwardly by the compressed spring 38 and its head 29 forcibly strikes the anvil 25. When the body 14 is moving downwardly as just described, and before the release of the latch block 39, the shoulder 22 passes downward below the anvil top 25. On the following return stroke or upward stroke of the body 14 the shoulder 22 moves up into engagement with the hammer head 29 so that the hammer 27 is picked up by the upwardly moving body 14. The body 14 moves upwardly until the block 39 reaches the upper end of the mandrel 15 at which time the spring 42 moves the block inwardly to its latched position illustrated in Figs. 3 and 5. At this time the shoulder 23 reaches or approaches the flange 24 and the parts are in the positions illustrated in Figs. 3 to 7, inclusive.

It is preferred to provide means for assisting the return movement of the body 14 relative to the mandrel 15 and to absorb shock which may result from sudden downward movement of the body with respect to the mandrel. A helical spring or coiled spring 44 is arranged under compression between the lower end of the stem section 31 and the bottom of the opening 35. The spring 44 is lighter or weaker than the spring 38.

It is preferred to maintain a bath of oil or other suitable liquid in the body 14 to lubricate the various parts and to exclude the drilling fluid and well fluids which usually contain abrasive matter. A packing gland 45 is provided in the shoe 21 to seal around the mandrel 15 so that the lower end of the body assembly or outer assembly is closed. The notches in the flanges 28 and the clearance around the hammer 27 and the stem sections 30 and 31 permit a continuous column or body of the oil or other liquid to be contained or stored in the outer tubular assembly. A floating annular plunger or follower 46 is provided in the annular chamber within the barrel 18 at the upper end of the column of oil or other liquid contained in the tool. A plurality of spaced lateral ports 47 is provided in the wall of the stem section 30 above the follower 46 to maintain the upper portion of the barrel 18 in communication with the string S so that the upper side of the follower 46 is subjected to the pressures existent in the string S and well bore. With this arrangement the oil or fluid contained in the body 14, shoe 21 and the lower portion of the barrel 18 is held under substantially the same pressures as the fluid in the string S and the well so that there is little tendency for fluid to leak into or out of the hollow sealed assembly.

The floating follower 46 may be of any selected construction. As illustrated in Fig. 3 of the drawings the follower 46 may be made up of a plurality of spaced rings 48 with upwardly and downwardly facing chevron packing 49 ar-

ranged between the opposing ends of the rings 48. The assembly of the rings 48 and packing 49 is held together in the correct operating relation by spaced screws or bolts 50. When the mechanism or impact generator 10 is operated the follower 46 is free to ride up and down as the volume of the chamber in the tool, etc. increases and decreases. The floating follower 46 completely separates the contained oil, or the like, from the well fluids and prevents contamination of the oil or contained fluid.

The directional drilling bit 12 is secured to the lower end of the impact generator 10. In the drawings I have shown the bit 12 connected with the mandrel 15 by a suitable collar or connection 52. The bit 12 may be varied greatly in design, construction, etc. The bit 12 is preferably of a type which operates effectively by a hammer action or percussive action. In the construction illustrated the bit 12 is an elongated thick walled tubular member having an enlarged head at its lower end which presents a multiplicity of downwardly directed teeth 53. There may be an annular series of teeth 53 surrounding the lower end of the opening 54 in the bit. The teeth 53 are adapted to form an annular or cylindrical bore in the earth formation having a diameter smaller than the main well bore B but sufficiently large to receive the directional drilling equipment with clearance so that well fluids may be circulated through the directional bore D if desired.

Fig. 9 illustrated another form of bit that may be used with the apparatus. The bit 12^a shown in Fig. 9 is secured to the lower end of the mandrel 15 by the connecting member or sub 52 in the same way as the bit 12. The bit 12^a is a generally cylindrical member provided with a sloping or pitched lower end 55 formed or designed to cut into the earth formation. The bit 12^a is a "spudding bit" and is effective in starting a new bore or a directional bore D. It is to be understood that the bit 12^a is tubular or provided with a central vertical opening similar to the opening 54 of the bit 12.

The orienting means 13 is such that the position of the bit 12 or 12^a may be accurately determined prior to initiating the directional drilling operations so that the bit may be re-positioned if this is found necessary. The orienting means 13 includes a locating seat or orienting seat 56 at the bit 12 or 12^a. In the particular case illustrated the seat 56 is formed in the sub 52 and is in the nature of an upwardly facing annular surface on the interior of the sub. The seat 56 is sloped or pitched at a substantial angle and the rotative position of the angular plane of the seat 56 is known. In other words, the seat 56 bears a given rotative position with respect to the bit 12 or 12^a, the mechanism 10 and the string S. The opening through the sub 52 is enlarged above the seat 56 to constitute a cylindrical socket 57.

The orienting means 13 further includes a device or object to be dropped or lowered through the string S to cooperate with the seat 56. This object will be termed a go-devil 58. The go-devil 58 may be run into and out of the string S on a cable or line L. The go-devil 58 is generally cylindrical and is proportioned to be received in the socket 57 and has a rope socket 59 on its upper end receiving line L. A face 60 is provided on the lower end of the go-devil 58 to cooperate with or mate with the seat 56. The face 60 is complementary to the seat 56, being

sloped or pitched to conform to the seat. The seat 56 and face 60 are such that the go-devil 58 automatically turns when the face comes into engagement with the seat and the go-devil turns until the seat and face are in flush even engagement and therefore in the same rotative position. Thus, the go-devil 58 automatically assumes a given orientation or rotative position with respect to the bit 12 or 12^a and the string S.

- 10 The self-locating or self-orienting go-devil 58 is associated with or carries a surveying instrument 61. The surveying instrument 61 may be in the nature of a single shot operable to make a record of the rotative position and angularity 15 of the instrument. As surveying instruments of the single shot type are well known to those skilled in the art the details of the instrument have been omitted from this disclosure. As illustrated in the drawings the surveying instrument 61 is an elongate tubular member secured to the go-devil 58 to extend downwardly therefrom. The instrument 61 is proportioned to pass through the sub 52 and the opening 54 of the bit with suitable clearance and is designed so that 20 its sensitive magnetic means or compass means is housed in that portion of the instrument which protrudes below the bit 12 or 12^a. As illustrated in Figs. 1 and 9 of the drawings the instrument 61 projects a substantial distance from the lower end of the bit 12 or 12^a when in the operative position at the bit. The instrument 61 is fixed to the go-devil 58 and when the go-devil comes to rest on the seat 56 the surveying instrument 61 is in a given or non-rotative position 25 with respect to the bit 12 or 12^a and the string S. Accordingly, the record produced by the instrument 61 accurately indicates both the rotative position and the angularity of the bit 12 or 12^a.
- 30 40 In operating the apparatus and in carrying out the method of the invention it is usually desirable to determine the direction and the angularity of the intended side track bore or directional bore D. With these factors in mind 45 the section 11 is formed to have the desired or required curvature or angularity. The equipment is assembled as illustrated in the drawings with the mechanism or impact generator 10 secured to the lower end of the section 11 and provided with a selected form of bit 12 or 12^a. It is to be understood that the section 11 is shaped, bent or made angular prior to running the equipment into the well. The string S is assembled and run into the well in the usual manner until 55 the bit 12 or 12^a assumes a position adjacent the bottom of the well bore B. Owing to the curvature or angularity of the section 11 the bit 12 or 12^a will assume a position adjacent the wall of the bore B and the string S or the upper 60 part of the section 11 will assume a position adjacent the well wall opposite and above the bit. When the string has been lowered to the position where the bit 12 is adjacent the well bottom the go-devil 58 carrying the surveying instrument 61 is run into the string S on the line L. The go-devil is lowered until its face 60 cooperates with the seat 56. As above described, this cooperation automatically brings the surveying instrument 61 to a given and known rotative position with respect to the bit 12 or 12^a and the string S. The surveying instrument 61 is operated or permitted to operate to produce its record and is then withdrawn from the well.
- 65 70 Examination of the record produced by the surveying instrument 61 reveals the position of

the bit 12 or 12^a in the well bore B. In most cases it will be found that the bit is not in the correct rotative position to begin the directional drilling operations and it is necessary to bring the bit to the correct position. This is done by merely turning the string S to re-locate the bit. The bit 12 or 12^a may be suspended from the bottom of the well bore B or may rest lightly on the well bottom so that it may be freely turned to its new position. When the string S is suspended from the top of the well to hold the bit 12 free the clutch parts 26 are engaged and the bit may be readily turned to the new position with the assurance that it will be correctly located. Following these operations it may be desired to determine if the bit 12 or 12^a has been moved to the correct position. This may be done by running the go-devil 58 and surveying instrument 61 down through the string S to again engage the go-devil on the seat 56. The surveying instrument 61 takes another reading or makes another record and when the line L is withdrawn this record may be examined to determine if the bit 12 is in the correct position. In this way the directional drilling bit may be accurately oriented.

Following the locating or orienting of the bit 12 the string S is lowered to engage the bit against the earth formation and the string is then reciprocated to operate the mechanism or impact generator 18. The impact mechanism or generator 18 operates as described above to impart heavy downward blows or impacts to the section 11 and bit 12. The bit 12 or 12^a is operated by these impacts and cuts away the earth formation to form the directional bore D. It is important to note that the bit is operated to form the directional bore D without rotating the operating string S and therefore without altering the position of the orienting bit. The directional drilling bit 12 forms a directional bore D whose position or direction has been accurately determined by the above described orienting operations and whose angularity has been determined by giving the section 11 the intended or required curvature or angularity. The directional bore D may be drilled to the required depth by means of the directional drilling equipment and circulation fluid may be pumped down through the string to discharge at the bit during these drilling operations. When the directional bore D has been drilled to a suitable depth the equipment is withdrawn from the well and regular rotary drilling operations may be resumed to continue the directional

drilling. In some cases it may be desired or necessary to enlarge the bore D.

Having described typical preferred forms and applications of my invention, I do not wish to be limited or restricted to the specific details herein set forth, but wish to reserve to myself any variations or modifications that may appear to those skilled in the art and fall within the scope of the following claims.

- 10 Having described my invention, I claim:
1. Well drilling apparatus for use on a tubular well drilling string comprising a curved tubular string section, an impact bit and means for operating the bit comprising an element on the bit, an element on said section, one element being a tubular body, the other a tubular mandrel shiftably and telescopically related to the body, a hammer mechanism in the body operable by telescopic movement of the elements to impart downward blows to the bit, and means for maintaining a lubricant bath in the body.
- 15 2. Well drilling apparatus for use on a tubular well drilling string comprising a curved tubular string section, an impact bit, and means for operating the bit comprising an element on the bit, an element on said section, one element being a tubular body, the other a tubular mandrel shiftably and telescopically related to the body, a hammer mechanism in the body operable by telescopic movement of the elements to impart downward blows to the bit, and means for maintaining a lubricant bath in the body.
- 20 3. Well drilling apparatus for use on a tubular well drilling string comprising a curved tubular string section, an impact bit, and means for operating the bit comprising an element on the bit, an element on said section, one element being a tubular body, the other a tubular mandrel shiftably and telescopically related to the body, a hammer mechanism in the body operable by telescopic movement of the elements to impart downward blows to the bit, and means for maintaining a lubricant bath in the body.
- 25 4. Well drilling apparatus for use on a tubular well drilling string comprising a curved tubular string section, an impact bit, and means for operating the bit comprising an element on the bit, an element on said section, one element being a tubular body, the other a tubular mandrel shiftably and telescopically related to the body, a hammer mechanism in the body operable by telescopic movement of the elements to impart downward blows to the bit, and means for maintaining a lubricant bath in the body.
- 30 5. Well drilling apparatus for use on a tubular well drilling string comprising a curved tubular string section, an impact bit, and means for operating the bit comprising an element on the bit, an element on said section, one element being a tubular body, the other a tubular mandrel shiftably and telescopically related to the body, a hammer mechanism in the body operable by telescopic movement of the elements to impart downward blows to the bit, and means for maintaining a lubricant bath in the body.
- 35 6. Well drilling apparatus for use on a tubular well drilling string comprising a curved tubular string section, an impact bit, and means for operating the bit comprising an element on the bit, an element on said section, one element being a tubular body, the other a tubular mandrel shiftably and telescopically related to the body, a hammer mechanism in the body operable by telescopic movement of the elements to impart downward blows to the bit, and means for maintaining a lubricant bath in the body.
- 40 7. Well drilling apparatus for use on a tubular well drilling string comprising a curved tubular string section, an impact bit, and means for operating the bit comprising an element on the bit, an element on said section, one element being a tubular body, the other a tubular mandrel shiftably and telescopically related to the body, a hammer mechanism in the body operable by telescopic movement of the elements to impart downward blows to the bit, and means for maintaining a lubricant bath in the body.
- 45 8. Well drilling apparatus for use on a tubular well drilling string comprising a curved tubular string section, an impact bit, and means for operating the bit comprising an element on the bit, an element on said section, one element being a tubular body, the other a tubular mandrel shiftably and telescopically related to the body, a hammer mechanism in the body operable by telescopic movement of the elements to impart downward blows to the bit, and means for maintaining a lubricant bath in the body.
- 50 9. Well drilling apparatus for use on a tubular well drilling string comprising a curved tubular string section, an impact bit, and means for operating the bit comprising an element on the bit, an element on said section, one element being a tubular body, the other a tubular mandrel shiftably and telescopically related to the body, a hammer mechanism in the body operable by telescopic movement of the elements to impart downward blows to the bit, and means for maintaining a lubricant bath in the body.
- 55 10. Well drilling apparatus for use on a tubular well drilling string comprising a curved tubular string section, an impact bit, and means for operating the bit comprising an element on the bit, an element on said section, one element being a tubular body, the other a tubular mandrel shiftably and telescopically related to the body, a hammer mechanism in the body operable by telescopic movement of the elements to impart downward blows to the bit, and means for maintaining a lubricant bath in the body.

ARTHUR L. ARMENTROUT.
